UNITED STATES PATENT OFFICE

ARCHIBALD W. PAULL, OF WHEELING, WEST VIRGINIA, AND JOHN F. MILLER, OF MARTIN'S FERRY, OHIO.

MANUFACTURE OF LAMP OR LANTERN GLOBES, CHIMNEYS, &c.

SPECIFICATION forming part of Letters Patent No. 256,158, dated April 11, 1882.

Application filed January 19, 1882. (No model.)

To all whom it may concern:

Be it known that we, ARCHIBALD W. PAULL, of Wheeling, Ohio county, and State of West Virginia, and JOHN F. MILLER, of Martin's Ferry, county of Belmont, and State of Ohio, have jointly invented certain new and useful Improvements in the Manufacture of Lamp or Lantern Globes, Chimneys, &c., of which the following is a full, clear, and exact description, reference being had to the accompanying drawings, and to the letters of reference marked thereon.

Our invention has relation to the manufacture of globes, chimneys, shades, reflectors, and similar articles intended to surround the flame or light of any illuminating apparatus—such as lamps, lanterns, head-lights, gas-burners, vapor-burners, electric lights, &c.

The object of our invention is to produce such articles with a lens or with lenses, forming a part thereof, for the purpose of more effectively concentrating or otherwise controlling the light upon the same principles and for like purposes as separate lenses have been heretofore used—as, for instance, like the well-known bull's-eye lens in the common "dark-lantern," in the light-house lamp, &c.

Heretofore it has been proposed to swell or bulge or enlarge a portion of the globe or chimney to form a lens thereon. This does not afford the desired refraction and concentration of the light, for it leaves the so-called "lens" part of the globe or chimney of substantially uniform thickness throughout, and that only about the thickness of the walls of the chimney or globe. The lenses so formed are of no practical use for the purposes intended. We overcome these defects and produce a chimney or globe, &c., having a reliable, practical, and efficient lens of proper construction, forming a part of the article or made integral therewith; and to accomplish this our invention involves certain novel and useful improvements in the manufacture and in the means employed to carry them out, as will be herein first fully described, and then pointed out in the claims.

To illustrate our improvements we have chosen an ordinary form of lantern or lamp globe and a mold suitable for making it; but it should be understood that the mere form or shape of the globe or protector is in no wise

essential to the invention, which can be practiced in connection with any form, pattern, or size.

In the accompanying drawings, forming part 55 of this specification, Figure 1 is a perspective view of a mold made in two parts and adapted to receive the lens, which mold is one form that may be employed in carrying out our invention. Fig. 2 is a horizontal section of the 60 mold in the position indicated in Fig. 1; and Fig 3 is a similar view, showing the two parts of the mold closed together. Fig. 4 is a horizontal section through the mold and the contained chimney or globe with the lens formed 65 thereon in accordance with our invention. Fig. 5 is an elevation of a tongs or pinchers, which may be employed for grasping and locating the lens in the cavity provided for it in the mold; and Fig. 6 is an edge view of one form of lens 70 proposed to be applied upon the globe or chimney. Fig. 7 is a section, and Fig. 8 a plan or face view, of a modified form of lens, (commonly known as the "Fresnel" lens,) which may be applied instead of the plain lens. Fig. 75 9 is a sectional view and partial elevation of an ordinary form of globe or chimney completed in accordance with our invention.

These illustrations, in connection with the following explanations, will be found sufficient 80 to enable others skilled in the art to which our improvements pertain to practice and use our invention, and in all the figures of the drawings like letters of reference, wherever they occur, indicate corresponding parts.

A are two parts of a glass mold, formed for the purpose of shaping the chimney. These parts are suitably hinged or otherwise connected, so that they can be opened to remove the completed article, and so that when properly closed together they will match in a manner well understood. A cavity, a, is formed in the walls of the mold, communicating with the interior thereof, and one half in one section, the other half in the opposite section, of 90 the mold, as indicated, which cavity is for the reception of a lens already formed.

B is the lens, which, as will be observed, has an edge so formed that it will be readily encompassed by the margin of the cavity in the 100 mold, and when placed in this cavity be firmly held with its inner face exposed to the interior

of the mold. The lens B is first formed or molded in propersize and shape to correspond with cavity *a*. While still hot it is grasped by any convenient implement, as the tongs C, 5 which barely touch the lens at two points on its margin, and is held in proper place in the opening of the mold. The two sections of the mold are then quickly closed together, so as to support the lens in the cavity *a*, the tongs C 10 being withdrawn before the closing is completed, for which purpose they are preferably made of thin metal, so as to take up but little room between the two parts of the mold. As soon as the lens is located and the mold closed 15 the glass for the chimney or globe is introduced and blown in the usual manner to fill the mold, and the article completed in a manner well understood. By following this method it will be observed that the finishing of the 20 globe or chimney upon the lens adds to the thickness of the lens a layer of material equal in thickness to that of the other part of the walls of the article, preserving an inner face parallel with the original face of the lens, so 25 that if the inner face of the separate lens be made flat, it will still appear so in the completed article. In like manner, if it be desired to employ a lens with a concave or convex inner face, the same shape will be preserved after the additional thickness of material is applied. The 30 lens being placed in the mold in a highly-heated state, and the material for the mold or chimney immediately blown upon it or against it, a thorough welding of the parts takes place, 35 leaving no joint or seam between the material of the globe or chimney, but bringing the whole out in one homogeneous mass. A seam or joint between the parts would of course destroy the effectiveness of the lens. The sectional view 40 Fig. 3 indicates the separate lens as placed in its cavity in the mold, ready to be welded with the material of the globe or chimney; and in Fig. 4 the section indicates the completed article, wherein the thickness of the lens is increased by an amount of material equal to that 45 of the walls of the article. The sharp edge of the lens, as shown, facilitates its insertion in the cavity of the mold and insures its being firmly held all around when the mold is closed. 50 This edge may be varied in any suitable way, if desired.

Instead of the plain bull's-eyelens, any other form of lens may be applied by properly preparing the mold to receive it.

55 In Figs. 7 and 8 we have shown a ribbed or corrugated lens, intending to indicate thereby that the size and shape of the lens are in no way essential.

It will appear that to blow or mold a lens 60 upon a globe or chimney, which lens shall be thicker in the center than at the edges, is impracticable without the application of the separate lens, substantially as above indicated.

The utility of the globe or chimney with 65 the lens forming a part thereof is sufficiently

obvious. It enables one to employ the illuminating apparatus for its usual purposes without interference, and at the same time makes a globe or protector by which the light may be concentrated or directed toward any point 70 at will.

Of course the invention will be found most serviceable in hand-lanterns or in those intended to be carried about; but, as before explained, the improved article may be applied 75 upon any form of illuminator. When applied upon the shades for house-lamps, particularly upon those having a base of translucent or transparent material and known as "base-shades," the lens affords means for throwing 80 the light across a room in a powerful manner, and thus adds to the desirable qualities of such shades, as will be readily understood.

Of course the chimney or globe, &c., may be made up in accordance with our invention of 85 the materials usually employed in the manufacture of similar articles without the addition of the lens.

To apply two or more lenses to one article the mold must be suitably modified to accommodate the increased number. 90

When the flat-faced lens is to be applied upon a cylindrical-walled article, substantially as shown in Fig. 9, the mold should be so formed as to bring the walls of the article out 95 to the edge of the cavity by any gently-curved surface, as at *b*. If the face of the article be flat or plain, as sometimes may occur, then the mold has only to be supplied with a cavity for the lens, as at *a*. The lens might be 100 formed with an inner face curved so as to correspond with the curvature of the walls of the article, in which case the inclined part *b* need not be provided for.

Having now fully described our invention, 105 which we claim as new, and desire to secure by Letters Patent, is—

1. As a new article of manufacture, a lamp chimney or globe composed of glass and formed with a united lens which is of a greater 110 thickness than the glass composing the body of the globe, substantially as herein described.

2. A sectional mold for the manufacture of lamp-chimneys or like articles, having the outlines of the chimney to be formed and provided with a recess, *a*, in each section of such construction for receiving and retaining the lens to be united, and a space around the lens for the admission of the molten glass to the lens in the process of forming the chimney, 120 as set forth.

In testimony that we claim the foregoing we have hereunto set our hands in the presence of two witnesses.

ARCHIBALD W. PAULL.
JOHN F. MILLER.

Witnesses:

JOHN BUCKLER,
F. W. HANAFORD.
